UNITED STATES PATENT OFFICE.

ERWIN L. PIERCE, OF EVERETT, MASSACHUSETTS, ASSIGNOR TO CHARLES S. KNOWLES, OF NEW BEDFORD, MASSACHUSETTS.

OUTLET-BOX.

No. 904,011.

Specification of Letters Patent.

Patented Nov. 17, 1908.

Application filed August 31, 1907. Serial No. 390,879.

To all whom it may concern:

Be it known that I, ERWIN L. PIERCE, of Everett, in the State of Massachusetts, have invented a new and useful Outlet-Box, of which the following is a specification.

My invention relates to outlet boxes which are used for making or changing connections in electrical wiring.

The object of my invention is to provide an outlet box whose openings are adapted for use with different sizes of conduits, and my invention is an outlet box having one or more openings through its wall, each opening being closed when not in use by two or more removable stoppers which are so arranged that one may be removed to make an opening for one size of conduit while two may be removed for a larger size of conduit and so on.

20 A feature of my invention consists in having opposed stoppers in the openings of the box, that is, one stopper is removable in one direction only, while the opposed stopper is removable in the opposite direction only.

25 In the drawings Figure 1 is a bottom plan of an outlet box embodying my invention; Fig. 2 is a central vertical section of the box shown in Fig. 1; and Fig. 3 is a similar section showing different conduits in place.

30 My outlet box comprises body A with openings a, a, a, through its wall. The number and location of these openings are immaterial as they may vary with the uses to which the boxes may be put. These openings are to receive the conduits for the wires and it is desirable to have the openings adapted to receive different sizes of conduits. For example, there may be used a flexible metal pipe B or a rigid metal pipe B' or a 35 circular loom tubing B². It is the general custom to have two sizes of conduits so that a box whose openings are adapted for use with two sizes of conduit is highly important and desirable.

40 45 I have shown in the drawings a box with several openings and each opening has a stopper ring d within it and within the ring is a stopper d'. I prefer to punch the stopper ring from the box but not completely so that when a particular opening is to be used a blow of a hammer or other suitable tool will complete the removal of the stopper ring and leave the opening in condition to receive the conduit. The stopper d' is punched from the stopper ring but not com-

pletely for the same purpose as with the ring. This may be done by any suitable devices and it will be noted that although there will be relative movement between ring d and stopper d' yet the latter may remain 60 flush with the body of the box as is the case in the form shown in the drawings. There is an important effect due to the punching which is that the metal is left in such condition that the portion which has been partly 65 removed cannot as a practical matter be again returned to its original position but its complete removal must be had in the same direction in which it started. I am of the opinion that this effect is due in part 70 at least to the condition of the metal resulting from the shearing. I am also of the opinion that the partly removed portion becomes arched and therefore resists attempts to return it to its original position. However that may be the fact is that it is practically impossible to so return it. This effect is also had as to stopper d' with relation to ring d and the importance of it is that if it is desired to have a small opening a blow 75 from a hammer on stopper d' in the upward direction in Fig. 2 will remove that stopper but cannot remove the stopper ring because the latter's movement in that direction is resisted as above explained. The result will 80 be that the smaller opening is provided. If it is desired to have the larger opening, the blow of the hammer is applied downwardly but the stopper d' cannot move in this direction relatively to stopper ring d. The 85 latter, however, is in condition to move in this downward direction so that the blow will force both the ring d and stopper d' to the interior of the box, thus providing the 90 larger opening.

95 Several methods of connecting the conduits are shown in the drawings. For example, conduit B² is simply inserted in the opening; conduit B' is threaded to engage a nut outside of and a nut inside of the wall 100 of the box; and conduit B is connected to a cup which has a shoulder to engage the outside of the wall of the box and which is threaded to engage a nut on the inside of the wall of the box.

105 What I claim is:

1. An outlet box comprising a body with an opening through its wall; a stopper ring held in that opening but removable therefrom in one direction only; and a stopper 110

held in that ring but removable from the ring in the opposite direction only.

2. An outlet box comprising a body with an opening through its wall; an outer stopper partly punched from said body in one direction so as to be removable in one direction only; and an inner stopper punched from said outer stopper in the opposite direction so as to be removable in the opposite direction only.

3. An outlet box comprising a body with an opening through its wall; an outer stopper partly punched from said body; and an inner stopper partly punched from said outer stopper.

ERWIN L. PIERCE.
